UNITED STATES PATENT OFFICE.

WILLIAM B. CASWELL, OF NEWPORT, RHODE ISLAND, ASSIGNOR OF ONE-FIFTH TO
ANN E. CASWELL, OF NEWPORT, RHODE ISLAND.

WINDOW-SHADE-ROLLER BRACKET.

1,267,312.

Specification of Letters Patent. Patented May 21, 1918.

Application filed September 27, 1917. Serial No. 193,573.

To all whom it may concern:

Be it known that I, WILLIAM B. CASWELL, a citizen of the United States, residing at Newport, in the county of Newport and State of Rhode Island, have invented certain new and useful Improvements in Window-Shade-Roller Brackets, of which the following is a specification.

This invention relates to improvements in adjustable and detachable window shade brackets, and has for one of its objects to simplify and improve the construction and increase the efficiency and utility of devices of this character.

Another object of the invention is to provide a simply constructed device which may be applied without structural change to the window casings or frame without marring or otherwise deteriorating the same.

Another object of the invention is to provide a simply constructed device wherein the adjustable portion is held by friction only and adapted to shade rollers of various shapes and sizes.

With these and other objects in view the invention consists in certain novel features of construction as hereinafter shown and described and then specifically pointed out in the claims; and in the drawings illustrative of the preferred embodiment of the invention—

Figure 1 is a front elevation of the upper portion of a window including the casings and a portion of the upper sash with the improvement applied.

Fig. 2 is an enlarged transverse section on the line 2—2 of Fig. 1.

Fig. 3 is an enlarged perspective view of the blank from which the supporting portion or bracket of the improved device is constructed.

Fig. 4 is an enlarged perspective view of the supporting or bracket portion of the improved device completed.

Fig. 5 is an enlarged perspective view of one of the adjustable shade roller supports.

Corresponding and like parts are referred to in the following description and indicated in all the views of the accompanying drawings by the same reference characters.

The improved device includes a bracket or supporting member adapted to be attached to the window frame or casing and

a shade roller supporting member adapted to be slidably engaged with the bracket. The bracket portion of the device is formed from sheet metal, preferably steel, bent or "struck up" into the required shape, and including a body portion 10 having coacting U-shaped clefts in spaced relation whereby tongues indicated at 11 are produced. The free ends of the tongues are bent into flat hook-like shape as shown in Fig. 4 whereby an inwardly projecting lip 12 and stop 13 is formed on each tongue. The body portions of the tongues are also bent obliquely to the longitudinal plane of the body 10, and the body 10 together with its tongues being of steel, may be tempered and the tongues thus rendered resilient. The tongues 11 are pierced to receive the holding screws 14 whereby the bracket device is secured to the casing 15 or other portion of the window, and by directing the tongues obliquely to the plane of the body 10 of the bracket, the heads of the screws 14 may be utilized to compress the tongues, as hereafter explained.

An outwardly directed stop rib 16 is formed upon the body 10 between the confronting ends of the tongues 11, the rib being preferably produced by pressing a portion of the body outwardly, as illustrated in Fig. 2.

By this means the terminals 12 and the rib 16 coact with the tongues 11 to form a yieldable socket to receive a flat bar or plate 17 and hold the same by friction. At one end the bar 17 is bent at an angle to the body of the bar as shown at 21. The outwardly bent portion 21 will be perforated to receive the bearings or journals of a shade roller, the perforation at one side being circular to receive the circular journal at one end of the roller and the aperture of the member 21 at the other side slotted to receive the flat journal at the other end of the roller, the portion 21 serving the same purpose as the ordinary brackets of a curtain fixture. The material from which the bracket member is made possesses sufficient resiliency to cause the bent over portions 12 to engage the bar members 17 with sufficient force to hold them in position against the strains of the shade roller when in use, while at the same time when a sufficient force is applied, the bars are adjustable in

the brackets to enable the device to be adapted to shade rollers of various lengths, as will be obvious.

The device is simple in construction, can 5 be inexpensively manufactured and applied by any person without any previous skill or knowledge.

Having thus described the invention, what is claimed as new is:

- 10 A shade roller bracket comprising a flat body having coacting clamping tongues cut

out therefrom and struck up from the body and directed obliquely to the longitudinal plane of the same, each tongue having a clamping lip, and fastening devices piercing the tongues and adapted to secure the body to a support and force the clamping lips into frictional engagement with a shade roller support. 15

In testimony whereof I affix my signature. 20

WILLIAM B. CASWELL. [L. S.]
